US007601061B2

(12) **United States Patent**
Jackson

(10) Patent No.: US 7,601,061 B2
(45) Date of Patent: Oct. 13, 2009

(54) **GAMING MACHINE HAVING INDEPENDENT SPINNING FORMS AND MULTIPLE PAY LINES**

3,642,287 A	2/1972	Lally et al.
3,667,757 A	6/1972	Holmberg

A display is provided on which symbols may be provided for use in a slot-type wagering game. Symbols are displayed on sectioned geometrical shapes such as ovals, squares, circles, polygons, etc. Specific symbol combinations, particularly comprised of one symbol appearing on one section of each sectioned geometric shape or all symbols appearing on all sections of one sectioned geometric shape, may constitute a winning combination according to a predetermined pay table. Preferably the invention incorporates three 3-section circular reels, providing 30 different pay lines and an additional pay line incorporating all nine sections of the reels.

GAMING MACHINE HAVING INDEPENDENT SPINNING FORMS AND MULTIPLE PAY LINES

BACKGROUND OF THE INVENTION

1. Field of the Invention

The present invention relates to the field of mechanical and/or video wagering games, including multiple pay line video slot-type machines that are capable of producing certain winning combinations including, preferably, one or more progressive jackpot amounts.

2. Background of the Art

Competition in the gaming industry to attract a player and then retain the player's interest for protracted periods of time is an increasingly greater challenge. The environment in a casino is typically rich in stimulation, both auditory and visual. Consequently, it is an ongoing effort to attract a player to a given machine and then to subsequently encourage the player to stay at the machine based on the machine's game format and entertainment value.

Slot machines formed from a plurality of independently rotating reels, whether mechanical or video depictions of the mechanical reels, are traditional types of wagering games. Each physical reel has a reel strip around its circumference, on which are designated indicia. The circular reel is presented to the player so that the indicia on the strip show through a window on the machine's front. The player receives awards when combinations of predetermined indicia, especially related indicia that are oriented on a pay line, appear as a result of the wagered spin of the reels. Some machines also provide for a large jackpot or progressive jackpot that can produce potentially life-changing awards.

Such slot machines have evolved from having a single horizontal pay line centrally disposed on the reel to having a plurality of pay lines. Some of these pay lines are located horizontally, some vertically, some diagonally, others in corners and/or non-linear patterns. The most common pay lines have been provided as a) three symbols in a linear pattern taken from sets of frames on reels having 3 columns and 3 rows, or b) subsets of 3 to 5 symbols in a row taken from a set of three rows and five columns. The 3 rows by 5 column main game configuration is most typically known as a multiline game.

Winning combinations on the traditional 3-reel machines are easily recognized, but the setup itself discourages multiple pay lines. Conversely, the 3-rowx5-column configuration allows for multiple pay lines, but the winning combinations can be confusing and difficult to read. It is a challenge to provide new game play that would produce multiple wins, yet easily recognized wins. The frequency of "hits" on the traditional 3-reel machines can also be problematic. In most cases, the end result of a wagered 3-reel game is either a win worth at least the same as the wager, or a total loss of the wager, so the player may play many losing games in a row without experiencing a true winning event, increasing the total credits held by the player, or a smaller win event that reduces the rate of loss of credits. It would be desirable to have a simple-to-understand pay line system which can also provide more frequent "hits", even if these are wins that are less than the amount of wager. Smaller wins can give the player more time on the machine, which translates to more revenue for the casino. In addition, new techniques are needed to provide the player with jackpot opportunities, including multiple, varied jackpot awards.

U.S. Pat. No. 6,712,694 titled GAMING DEVICE WITH ROTATING DISPLAY AND INDICATOR THEREFORE;

U.S. Pat. No. 6,599,193 titled PROGRESSIVE GAMING DEVICE; U.S. Pat. No. 6,598,877 titled SLOT MACHINE USING PERIPHERAL GEARS ENGAGED BY MULTIPLE DRIVE SYSTEMS; U.S. Pat. No. 6,168,523 titled 5 BONUS AWARD FEATURE IN A GAMING MACHINE; U.S. Pat. No. 6,581,115 titled GAMING METHOD AND APPARATUS HAVING A PROPORTIONAL PAYOUT; U.S. Pat. No. 6,105,962 titled ROTATING DISKS SLOT MACHINE; U.S. Pat. No. 6,095,921 titled ELECTRONIC 10 AMUSEMENT DEVICE AND METHOD FOR OPERATING A GAME OFFERING CONTINUOUS REELS; and Published U.S. Patent Applications 20030045345 titled GAMING METHOD AND APPARATUS IMPLEMENTING A HIERARCHICAL DISPLAY GRID AND DYNAMICALLY GENERATED PAYLINES; 20030181231 titled PROGRESSIVE GAMING SYSTEM AND METHOD HAVING FRACTIONAL AWARDS; 20030216166 titled METHOD OF OPERATING A PROGRESSIVE GAMING DEVICE; 20030220134 titled APPARATUS HAVING 15 MOVABLE DISPLAY AND METHODS OF OPERATING SAME; 20030236116 titled SLOT MACHINE GAME HAVING A PLURALITY OF WAYS TO ISSUE A PERCENTAGE OF A PROGRESSIVE AWARD BASED UPON ANY WAGER LEVEL ("PERCENTAGE PROGRESSIVE"); 20040053687 titled GAMING DEVICE HAVING DISPLAY WITH MULTIPLE RADIALLY TRANSLATING INDICATORS; 20040157659 titled SLOT GAMING SYSTEM AND METHOD; 20040171417 titled METHOD AND APPARATUS FOR DISPLAYING A SYMBOL ON A 20 WHEEL ASSOCIATED WITH A GAMING APPARATUS; and 20040180716 titled GAMING DISPLAY WITH MOVEABLE INDICATOR AND METHODS OF USE describe various formats and games played on gaming apparatus, including slot-type gaming apparatus and video gaming apparatus.

Although there are many varieties of games available, there is room for new games and games that provide additional goals desired by players and casinos.

SUMMARY OF THE INVENTION

40 A screen is provided on which symbols may be provided for use in a slot-type wagering game. Symbols are displayed as distinct symbol elements, such as within frames, on sectioned geometrical shapes such as triangles, hexagons, rectangles, octagons, ovals and squares, but preferably on circles, etc. Specific symbol combinations, particularly comprised of one symbol appearing on one individual section of each sectioned geometric shape or all symbols appearing on all sections of one sectioned geometric shape, may constitute a winning combination according to a predetermined pay table. An additional payline comprised of all sections on all sectioned geometric shapes may provide for larger wins, including jackpot wins and progressive jackpot wins.

BRIEF DESCRIPTION OF THE FIGURES

FIG. 1 illustrates one embodiment of a screen setup of a base game with segmented circles as geometric shapes according to teachings herein.

60 FIG. 2 illustrates one embodiment of a screen shot where 40 pay lines could be available in the play of a base game.

FIG. 3 shows a screen shot of one possible sample stage of a game played with segmented circles as geometric shapes according to teachings herein.

65 FIG. 4 shows another screen shot of one possible sample stage of a game played with segmented circles as geometric shapes according to teachings herein.

FIG. 5 shows another screen shot of one possible sample stage of a game played with segmented circles as geometric shapes according to teachings herein.

FIG. 6 shows another screen shot of one possible sample stage of a game played with segmented circles as geometric shapes according to teachings herein.

FIG. 7 shows another screen shot of one possible sample stage of a game played with segmented circles as geometric shapes according to teachings herein.

FIG. 8 shows another screen shot of one possible sample stage of a game played with segmented circles as geometric shapes according to teachings herein.

FIG. 9 illustrates nine physical reels for use in a mechanical version of a game played with segmented circles as geometric shapes according to teachings herein.

FIG. 10 illustrates a cutaway front view of a mechanical slot machine with a game played with segmented circles as geometric shapes according to the teachings herein.

DETAILED DESCRIPTION OF THE INVENTION

Game play described herein may be implemented on existing and commercial mechanical, virtual/mechanical or video gaming apparatus on any of the many available formats and platforms merely by insertion of a game card or game software effecting the selections and rules and payouts according to the present game. The base game may also be implemented on a stepper mechanical reel format. The game may be operated on-line, in a banked set of gaming machines or independent machines with independent processors. The game can be programmed onto MAC, PC, LINUX, open or closed operating systems (as well as other or newer commercial systems) and can be displayed with standard CRT displays, plasma displays, LCD displays, LED displays, holographic displays and the like. The games may be operated with ticket-in/ticket-out crediting, coins, tokens, currency, credit cards, or gaming accounts as well understood by one skilled in the art. The following is intended to offer a general description and example of the technology of the game play and offer insight into distinctions from existing commercial or disclosed game play.

One general description of the method of playing a wagering game on a mechanical, virtual/mechanical or video gaming apparatus as described herein is as follows. The game format of 3-section circular reels and standard game symbols, i.e., cherries, bars and 7s, will be used in the description for consistency in the analogies of the play, but the game is of course not limited to that specific imagery. Before or upon initiation of the play of a single game (by placing a wager), the system provides a display screen having an area containing three or more sectioned shapes (called reels) within which symbols can be displayed. Preferably three 3-section virtual circular reels appear in a linear fashion from left to right. The three equal sections on each reel may be color-coded for more easy comprehension of the pay lines: the top section (at 12 O'clock) may be red, the right section (at 4 O'clock) may be blue and the left section (at 8 O'clock) may be green. Also shown on the screen may be the pay lines bet by the player, in this example 1 to 40 available pay lines. The forty pay lines are described as follows: each pay line consists of three reel sections, one section on each of the reels, or three sections on any one reel. Pay lines 1, 2, and 3 consist of three sections on each single reel from left to right, respectively. Pay lines 4, 5, and 6 consist of like sections on all reels (all 3 red sections, all 3 green sections, and all 3 blue sections, respectively). Pay lines 7 through 30 consist of all other possible different combinations of one section on each of the three reels. Pay lines 31

through 36 repeat the wagers on Pay lines 1 through 6, respectively (providing larger wins on the more obvious pay lines). Pay lines 37, 38, and 39 each repeat an additional wager on Pay lines 1, 2, and 3 respectively (providing the largest wins on the most obvious pay lines). If the player has bet all 39 pay lines, an additional wager would activate Pay line 40, consisting of all 9 sections of the three reels, and paying varying bonus awards for (preferably) receiving 9 like symbols, from the lowest-paying symbol to the highest-paying symbol. Each of these bonus awards may be a Progressive Jackpot. An alternate pay line configuration may utilize the Pay lines 1 through 30 as previously described, with Pay line 31 being the bonus 9-section pay line, with no repeat pay lines as previously described.

After the wager, play is initiated by the spinning of each reel in a circular fashion with virtual symbols streaming clockwise or counter-clockwise on the reels. The spinning reels and symbols stop, preferably one reel at a time from left to right. The symbols and/or blanks displayed are evaluated for wins according to a predetermined paytable. Wins may also be highlighted in the wagered pay lines area shown on the screen.

Reference to the Figures will assist in further understanding of the practice of the present invention.

FIG. 1 shows a monitor screen 2 having a display of a base game 12 showing three separate circular reels (14, 16, 18), and each reel divided into three equal 120° sections (20, 22, 24, 26, 28, 30, 32, 34, 36). Symbols 38 or "blanks" 40 are displayed on the colored-coded sections (20, 22, 24, 26, 28, 30, 32, 34, 36). A pay line payout chart 42 is also shown on the screen 2. The player control panel 10 incorporates buttons for various player wagering options, i.e., Pay lines Wagered 52, Credits Wagered per Pay line 54, Max Bet 56 and Spin 58.

FIG. 2 shows a chart 60 explaining the 40 pay lines 62 available in the play of the invention. Each of the 40 pay lines 62 is displayed on a set of three separate circular reels (14, 16, 18) with each pay line consisting of three color-coded sections (20, 22, 24, 26, 28, 30, 32, 34, 36) and labeled by three bullet symbols 64 to indicate that particular pay line.

FIG. 3 shows a monitor screen 2 with the player pressing the Max Bet 56 button (a wager of 40 pay lines and 10 credits bet per line) initiating the set of three separate reels (14, 16, 18) to spin 70 in a circular fashion.

FIG. 4 shows a possible result of the reel spin 70 in FIG. 3. One Red 7 symbol 72 is present on a section 20 of the first reel 14, one Red 7 symbol 74 is present on a section 28 of the second reel 16, and one Red 7 symbol 76 is present on a section 36 of the third reel 18, indicating a Win on Payline 11 78 of the pay line explanation chart 60 in FIG. 2 and highlighted in the pay line payout chart 42.

FIG. 5 shows another possible result of the reel spin 70 in FIG. 3. Three matching Bar symbols (80, 82, 84) are present on the third circular reel 18, indicating a Win on Pay lines 3 90, 33 92, and 39 94 as shown in the pay line explanation chart 60 in FIG. 2 and highlighted in the pay line payout chart 42.

FIG. 6 shows another possible result of the reel spin 70 in FIG. 3. A Cherry symbol 100 is present on a section 28 of the second reel 16, indicating Wins on Pay lines 2, 5, 9, 10, 11, 18, 19, 26, 27, 28, 32, 35, and 38 (110, 112, 114, 116, 118, 120, 122, 124, 126, 128, 130, 132, 134, respectively) as shown in the pay line explanation chart 60 in FIG. 2 and highlighted in the pay line payout chart 42.

FIG. 7 shows another possible result of the reel spin 70 in FIG. 3. Five Double Bar symbols (136, 138, 140, 142, 144) are present on the three circular reels (14, 16, 18), indicating Wins on Pay lines 3, 12, 13, 14, 33, and 39 (150, 152, 154,

156, 158, 160, respectively) as shown in the pay line explanation chart 60 in FIG. 2 and highlighted in the pay line payout chart 42.

FIG. 8 shows another possible result of the reel spin 70 in FIG. 3. Nine Double Red 7 symbols (170, 172, 174, 176, 178, 180, 182, 184, 186) are present on the three circular reels (14, 16, 18), indicating Wins on Pay lines 1-39 190 and a Win on Pay line 40 200 as shown in the pay line explanation chart 60 in FIG. 2 and highlighted in the pay line payout chart 42. Wins on the 40th Pay line constitute Jackpot Wins varying from 9 Cherries to the top Jackpot Win of Double Red 7s. Any or all of these Jackpot Wins may be a Progressive Award.

FIG. 9 shows an array of nine parallel physical circular reels (300, 302, 304, 306, 308, 310, 312, 314, 316), each physical reel having a plurality of various indicia 318 on a reel strip 320. Reels 1 300, 2 302 and 3 304 form a left-hand grouping, with Reel 1 300 and Reel 3 304 centrally positioned along the same plane and Reel 2 302 positioned on a higher plane. Reels 4 306, 5 308 and 6 310 form a center grouping, with Reel 4 306 and Reel 6 310 centrally positioned along the same plane and Reel 5 308 positioned on a higher plane. Reels 7 312, 8 314 and 9 316 form a right-hand grouping, with Reel 7 312 and Reel 9 316 centrally positioned along the same plane and Reel 8 314 positioned on a higher plane. All nine reels (300, 302, 304, 306, 308, 310, 312, 314, 316) rotate 330 independently upon activation.

FIG. 10 shows a cutaway view of a slot machine front panel 340, displaying nine cutout windows (350, 352, 354, 356, 358, 360, 362, 364, 366), exposing nine symbols (370, 372, 374, 376, 378, 380, 382, 384, 386) located on nine parallel physical circular reels (300, 302, 304, 306, 308, 310, 312, 314, 316). A first circular wheel 392 is shown, its 3-sectioned design framing windows 350, 352, 354. The first circular wheel 392 may spin 390 and stop before the main physical reels 300, 302, 304 stop. A second circular wheel 396 is shown, its 3-sectioned design framing windows 356, 358, 360. The second circular wheel 396 may spin 394, stopping after the first circular wheel 392 stops and before the main physical reels 306, 308, 310 stop. A third circular wheel 400 is shown, its 3-sectioned design framing windows 362, 364, 366. The third circular wheel 400 may spin 398, stopping after the second circular wheel 396 stops and before the main physical reels 312, 314, 316 stop. The outcome of the nine-symbol (370, 372, 374, 376, 378, 380, 382, 384, 386) display would be paid according to the wager and a predetermined pay table.

Another way of describing the method of play and the appearance of the games in a wagering device would be as a method of playing a wagering game on a gaming device or apparatus that displays symbols and provides awards on the appearance of predetermined symbols or predetermined arrangements of symbols. The method would comprise: a) a player placing a wager within the wagering game; b) the device or apparatus providing at least three defined areas that can display at least three active symbols within each defined area, each area being divided into distinct sub-areas where the symbols can be provided. These areas could abut each other, slightly overlap, or be completely separate, as long as distinct sub-areas remained available where the position and appearance of displayed symbols could be easily distinguished by visual observation. Symbols are randomly selected (e.g., by a random number generator, mapping, template provision, etc.) to appear within each distinct sub-area. The wager is resolved by determining whether the symbols selected causes a win, tie or loss in the appearance of predetermined symbols or predetermined arrangements of symbols under rules of the wagering game, as exemplified above. The three defined areas are

preferably geometric shapes, and more preferably three identical geometric shapes (that is each of the three shapes are identical to the other two shapes). The three identical geometric shapes may be selected from the group consisting of circles, ovals and polygons, equilateral polygons or not. For example, the three identical geometric shapes may selected from the non-limiting group consisting of circles, triangles, squares, rectangles, hexagons and octagons. The paylines within the geometric shapes are predetermined orders or combinations of sub-areas within the geometric shapes. The sub-areas may be demarcated by lines within the areas for enhanced visualization of the sub-areas, which may be equal or unequal in area within the at least three areas. The symbols may appear to move within the areas and between sub-areas.

Although specific examples and specific images have been provided in this discussion, these specifics are intended to be only support for the generic concepts of the invention and are not intended to be absolute limits in the scope of the technology discussed.

What is claimed:

1. A method for operating a gaming device, said method comprising:

for a single play of a game:
enabling a wager to be placed on a payline;
causing a display device to display a plurality of areas, each of said areas divided into a plurality of sub-areas;
for at least one but less than all of the sub-areas of each of

the areas, randomly determining a symbol from a plurality of different symbols into display in said sub-area, and causing the display device to display said randomly determined symbol in said sub-area;

for each of said areas, randomly determining one of the sub-areas of each of the areas which defines the payline, and causing the display device to display an indication of said randomly determined sub-areas which define the payline, wherein for each of said areas, the random determination of any symbol to display in any sub-area of said area is separate from the random determination of which sub-area of said area defines the payline; and determining if any randomly determined and displayed symbols in the sub-areas which define the payline are one of a plurality of winning symbol combinations, and if any randomly determined and displayed symbols along the payline are one of said plurality of winning symbol combinations, causing the display device to display an award for said winning symbol combination.

2. The method of claim 1, wherein said areas are geometric shapes.

3. The method of claim 2, wherein the displaying symbols in said sub-areas includes rotating said geometric shapes.

4. A method for operating a gaming device, said method comprising:

for a single play of a game:
causing a display device to display a plurality of areas, each of said areas divided into a plurality of sub-areas;
for at least one but less than all of the sub-areas of each of the areas, randomly determining a symbol from a plurality of different symbols to display in said sub-area, and causing the display device to display said randomly determined symbol in said sub-area;

randomly determining at least one of the sub-areas in each of said areas to be evaluated to determine if winning symbols are displayed in said sub-areas, and causing the display device to display an indication of said randomly determined sub-areas which will be evaluated to determine if winning symbols are displayed in said sub-areas, wherein for each of the areas, the random determination

of any symbol to display in any sub-area of said area is separate from the random determination of which sub-areas of said area are to be evaluated to determine if winning symbols are displayed; and

determining if any award is associated with any randomly determined symbols displayed in the randomly determined sub-areas, and if any award is associated with any randomly determined symbols, causing the display device to display said award.

5. The method of claim 4, wherein said areas are geometric shapes.

6. The method of claim 5, wherein the displaying symbols in said sub-areas includes rotating said geometric shapes.

7. A gaming device comprising:

10 at least one display device operable to display a plurality of areas, each of said areas divided into a plurality of sub-areas;

at least one input device; and

15 at least one processor configured to operate with the at least one display device and the at least one input device to: for a single play of a game:

(i) enable a wager to be placed on a payline,

(ii) for at least one but less than all of the sub-areas of each 20 of the areas, randomly determine a symbol from a plurality of different symbols to display in said sub-area, and causing the display device to display said randomly determined symbol in said sub-area,

(iii) for each of said areas, randomly determine one of the 25 sub-areas of said areas which defines the payline, and causing the display device to display an indication of said randomly determined sub-areas which define the payline, wherein for each of said areas, the random determination of any symbol to display in any sub-area of said area is separate from the random determination of which sub-area of said area defines the payline, and

(iv) determine if any randomly determined and displayed 30 symbols in the sub-areas along the payline are one of a plurality of winning symbol combinations, and if any randomly determined and displayed symbols are one of

said winning symbol combinations, and cause the display device to display an award for said winning symbol combination.

8. The gaming device of claim 7, wherein said areas are geometric shapes.

9. The gaming device of claim 8, wherein said display of symbols sub-areas includes rotating said geometric shapes.

10. A gaming device comprising:
at least one display device operable to display a plurality of areas, each of said areas divided into a plurality of sub-areas;

at least one input device; and

at least one processor configured to operate with the at least one display device and the at least one input device to: for a single play of a game:

(i) for one of the sub-areas of each of the areas, randomly determine a symbol to display in said sub-area, and cause the display device to display said randomly determined symbol in said sub-area,

(ii) randomly determine at least one of the sub-areas in each 15 of said areas to be evaluated to determine if winning symbols are displayed in said sub-areas, and causing the display device to display an indication of said randomly determined sub-areas which will be evaluated to determine if winning symbols are displayed in said sub-areas, wherein for each of the areas, the random determination of any symbol to display in any sub-area of said area is separate from the random determination of which sub-areas of said area are to be evaluated to determine if winning symbols are displayed, and

(iii) determine if any award is associated with any randomly determined symbols displayed in the randomly determined sub-areas, and if any award is associated with any randomly determined symbols, causing the display device to display said award.

11. The gaming device of claim 10, wherein said areas are geometric shapes.

12. The gaming device of claim 11, wherein said display of a symbol in said sub-areas includes rotating said geometric shapes.
